UNITED STATES PATENT OFFICE.

WILLIAM J. CARSE, OF LAIRD, COLORADO.

SHOCKER.

1,288,833.

Specification of Letters Patent. Patented Dec. 24, 1918.

Application filed July 19, 1917. Serial No. 181,610.

To all whom it may concern:

Be it known that I, WILLIAM J. CARSE, a citizen of the United States, residing at Laird, in the county of Yuma and State of Colorado, have invented certain new and useful Improvements in Shockers, of which the following is a specification.

This invention relates generally to hay shockers.

10 The invention aims primarily to generally simplify and improve hay shockers, and to generally reduce the cost of labor incident to the hay gathering and shocking processes.

15 A further object of the invention is to provide a shocker which may be used in connection with any preferred type of gathering or collecting mechanisms for the hay, and which receives the bundles and firmly 20 forms the same into a shock.

Still further and particular objects reside in providing a mechanism of the character set forth which shall be of extremely simple and inexpensive construction, which is composed of but few inexpensive and readily 25 assembled parts, all of the said parts being so constructed and assembled as to minimize the opportunity for wear, breakage, or derangement, which is easy and simple of operation, and which will prove thoroughly 30 efficient and practical in use.

With these objects in view together with others which will appear as the description proceeds, the invention resides in the novel 35 formation, combination and arrangement of parts, all as will be described more fully hereinafter, illustrated in the drawings and particularly pointed out in the claims.

In the drawings:

40 Figure 1 is a side elevation of a shocker constructed in accordance with the invention, the shocker being illustrated as applied to a conventional form of gathering machine.

45 Fig. 2 is a top plan view of the machine illustrated in Fig. 1.

Fig. 3 is a longitudinal sectional view taken through the shocker,

50 Fig. 4 is a bottom plan view of the shocker, and

Fig. 5 is a sectional view taken substantially upon line 5—5 of Fig. 3.

Referring now to the drawings, 10 indi-

cates generally the body of the vehicle, said vehicle being of any approved size and type, 55 and upon which a gathering machine is positioned. In the present instance this gathering machine includes shafts 11 and 12, upon the former of which sprockets 13 are affixed. Chains 14 pass over these 60 sprockets, and bars 15 connect the said chains. The chains pass over an inclined bottom plate 16, so that the bundles gathered by the pegs 17 on the bars 15 will be moved up the inclined way 16 and dropped 65 over the upper end thereof. The shaft 11 is also equipped with another sprocket gear or wheel 18, over which a chain 19 passes, the said chain also passing over a sprocket 20 affixed to an axle 21, the latter carrying 70 the ground-engaging wheels 22 as shown. It is obvious, therefore, that as this vehicle is drawn over the ground, the rotary movement developed in the axle 21 will be transmitted through the chain 19 to the sprocket 75 18, whereupon the shaft 11 will be rotated. The chain connection between the sprockets upon the shafts 11 and 12 cause the latter to rotate in unison. The vehicle may be propelled over the ground in any suitable 80 manner.

Rotatably mounted at the lower end of the vehicle and adjacent the rear thereof is a shaft 25. This shaft is disposed transversely of the vehicle, and is provided at 85 one end with a sprocket wheel 26, over which a chain 27 passes, the said chain also passing over a sprocket wheel 28 secured to the shaft 12 at the upper end of the shock conveyer. Mounted for rocking 90 95 movement at one end upon the shaft 25, intermediate the ends of the latter is a lever 29. This lever extends forwardly and normally is horizontally disposed, being supported at its extreme forward end by a cross member 30 upon the vehicle frame. An upwardly extending stud or spindle 31 is carried by the lever 29 directly above the shaft 25, and mounted for rotation upon this spindle is a shocker platform 32. This 100 platform is circular as shown, and is provided upon its under face with a beveled gear 33, the latter being in mesh with a similar gear 34 affixed to the shaft 25. The shaft 25 also carries a roller 35, the latter 105 bearing against the under face of the plat-

form 32, and the beveled gears and roller properly support the platform and evenly distributes the weight to which the platform may be subjected to the supporting 5 shaft 25.

It will be observed that the shocker platform 32 is disposed directly beneath the upper end of the inclined way 16, so that loose hay or bundles carried upwardly by the 10 conveyor at the forward end of the machine will be dropped upon the platform at substantially the central part. A deflector plate 36 is disposed transversely of the machine and upon the superstructure thereof, the 15 said plate being disposed at the upper end of the inclined bottom 16 and it will be understood that this plate may be adjusted so as to cause the bundles dropped beyond the end of the bottom to be deposited on or 20 away from the center of the platform 32. Any approved means may be provided for holding the deflector plate in its various positions of adjustment.

To hold the bundles deposited upon the 25 platform 32 from being thrown therefrom as the machine advances, a pair of guards are provided. The foremost of these guards, as indicated at 37, is hinged at one end as at 38 upon a post 39 extending upwardly from 30 one side of the vehicle frame, and the guard extends across to the other side of the vehicle frame, and is secured thereto by a spring 39'. It will be observed that the guard 37 is arcuate, and is concentric with 35 the table 32. The guard rises upwardly from the outer edges of the platform, and it is obvious that bundles deposited upon the latter will be held by the said guard against being thrown forwardly from the table. In 40 addition to be swingingly mounted upon the vertically disposed post 39, the guard is capable of sliding vertically thereon, and the lifting power for moving the guard 37 upwardly is supplied by the table 32 when the 45 latter is tilted by operation of the lever 29.

The rear portion of the table 32 is 50 enclosed by a guard indicated at 40. This guard is similar in construction to the guard 37, but is pivoted for horizontal swinging movement at its upper end to a laterally disposed rod 41 upon the vehicle.

The means for causing the table 32 to be tilted at the proper time, comprises a crank shaft 42. This crank shaft is mounted in 55 suitable bearings on the machine adjacent the lower end thereof, and is provided intermediate its ends with a crank portion 43. This crank portion engages in a slotted block 44, and the block 44 is carried by the 60 forward end of the lever 29. The outer ends of the rock-shaft 42 are provided with arms 46, to the outer ends of which the lower extremities of control-rods 47 are secured. The control rods 47 extend upwardly along 65 the side of the vehicle, and may be provided

at their upper ends with hand-grips 48, to facilitate the convenient operation of the same.

In operation, the machine is propelled over the ground by any suitable means. The 70 bundles or loose hay are gathered by the pegs 17 carried by the cross-bars 15 upon the conveyer, and these bundles are moved rearwardly and upwardly upon the bottom 16. As the machine travels over the ground, 75 the table 32 will be caused to rotate, and bundles deposited upon the platform 32, will, by centrifugal force, be swung to the outer edges of the table. The outward movement is, however, arrested by the 80 guards 37 and 40, and after a number of bundles sufficient to fill the platform have been delivered thereto, one of the operating rods 47 is moved so as to rock the crank-shaft 42. The rocking movement of the 85 crank-shaft causes the forward end of the lever 29 to be raised, whereupon the platform 32 is tilted upon the shaft 25. This tilting action causes the guard 37 to move 90 upwardly, and the weight of the bundles supported by the platform, in being swung against the rear guard 40 will cause the latter to swing rearwardly upon its horizontal pivot, and the bundles will be deposited upon the ground. After the depositing operation, the rods 47 may be again actuated 95 to move the parts back to normal position.

From this construction it is obvious that I have provided a shocker which is of extremely simple construction, and which is 100 capable of being efficiently operated with but little effort and may be maintained at little expense. The various parts which go to make up the completed machine are so constructed and assembled as to render the 105 possibility of breakage, wear or derangement exceedingly remote.

While the present is a disclosure of what is believed to be the preferred embodiment of the invention, it is to be understood that 110 the invention is not limited thereto, as various changes in the minor details of construction, proportion and arrangement of parts may be resorted to if desired without departing from the spirit of the invention 115 as defined by the appended claims.

What is claimed is:

1. In a shocker, a rotatable shaft, a lever rockably mounted at one end upon said shaft, a spindle extending upwardly from 120 said lever, a platform rotatably mounted on said spindle, a driving connection between said shaft and platform, a crank-shaft, a connection between the crank-shaft and the free end of said lever, whereby rotary movement of the crank-shaft will raise or lower the said end of said lever, and means for rocking said crank shaft.

2. In a shocker, a rotatable table tiltably mounted and designed to receive straw, a 130

vertically movable guard arranged in the path of movement of one side of said platform when the latter is tilted, and a horizontally swinging guard opposite to the 5 first mentioned guard designed to be swung outwardly by pressure of straw upon the platform.

3. In a shocker, a rotatable table tiltably mounted, a pair of arcuate guards for said 10 table, vertical posts beside said table, one of said arcuate guards being slidably mounted upon said posts and lying normally in the path of movement of one end of said table when the latter is tilted, and means for tilt- 15 ing said table.

4. In a shocker, a rotatable shaft, a platform rotatably mounted directly above said shaft, a power connection between said shaft and said platform whereby the latter will be 20 rotated upon rotary movement being applied

to the former, and guards at the forward and rear ends of said platform for holding straw thereon.

5. In a shocker, a rotatable shaft, a platform pivotally mounted directly above said 25 shaft, a power connection between said shaft and said platform, the said platform capable of being tilted, posts adjacent said platform, a guard slidably arranged upon said posts and extending partially around 30 said platform and in the path of movement of one end of the latter when the same is tilted, and means for tilting said platform.

In testimony whereof I affix my signature in presence of two witnesses.

WILLIAM J. CARSE.
